UNITED STATES PATENT OFFICE.

WALTER N. MARTIN, ANDREW J. THOMAS, AND EARL F. L. RUSSELL, OF DENVER, COLORADO.

AUTOMATIC TIME CIRCUIT-BREAKER.

No. 858,301.

Specification of Letters Patent.

Patented June 25, 1907.

Application filed July 25, 1904. Serial No. 218,120.

To all whom it may concern:

Be it known that we, WALTER N. MARTIN, ANDREW J. THOMAS, and EARL F. L. RUSSELL, all citizens of the United States, residing at the city and county of Denver and State of Colorado, have invented certain new and useful Improvements in Automatic Time Circuit-Breakers; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to means for breaking an electrical circuit at predetermined intervals the said means being operated by a clock mechanism of such a nature that the operating part of the clock may be set to operate the circuit breaking arm at any desired time.

In our improved construction, we have shown the circuit breaking arm mounted on the spring-actuated arbor which operates the escapement wheel which performs the alarm function of an alarm clock, the spring-actuated arbor being allowed sufficient movement to break the circuit. This circuit breaking arm is provided with a part which acts on an arm connected with the vibrating escapement, whereby the escapement wheel is locked from movement when the circuit breaking arm has reached the desired position or location with reference to the separated contacts, when the circuit is broken.

In clock mechanism of the character hereinafter shown and described, the spring for actuating the arbor is wound to a suitable tension and means are employed to lock the gears for operating the escapement wheel against movement in response to the action of the spring, until a certain time has elapsed; and the moment when the alarm mechanism is released, is determined by the person who sets the mechanism, the latter having a stem and a hand or pointer adapted to move around a small dial on the face of the clock.

Our improved circuit breaker is especially adapted for use in electric light circuits where it is desirable that the circuit be broken

at a given time. Its advantages will readily be understood since by reason of its automatic operation by clock mechanism, the circuit may be automatically broken at any time of day or night. It is evident that it is equally well adapted as a circuit breaker in any circuit other than a light circuit where it may become necessary to break the circuit or cut off the electrical current at a predetermined time.

Having briefly outlined our improved construction as well as the function it is intended to perform, we will proceed to describe the same in detail reference being made to the accompanying drawing in which is illustrated an embodiment thereof.

In this drawing, Figure 1 is a front view illustrating our improved circuit breaker shown in connection with a clock the latter being hinged to a suitable base upon which the separated contacts of the circuit are mounted. Fig. 2 is a similar view showing the clock mechanism thrown over upon its hinge to expose the rear side of the clock for purposes of winding or setting the alarm mechanism. Fig. 3 is a view illustrating the circuit breaking arm in connection with the portion of the clock mechanism more directly connected therewith. Fig. 4 is a similar view showing the circuit breaking arm in a different relative position. Fig. 5 is a section taken through the insulating base and illustrating one of the separated contacts. Fig. 6 is an end view of the base partly in section, and showing a hand-operated circuit breaker for closing and breaking the circuit independently of our improvement. Fig. 7 is a view of Fig. 3 looking in the direction of the arrow in said figure. Fig. 8 is a fragmentary detail view of an arbor showing a vertically movable gear mounted thereon and in section, the parts being shown on a larger scale.

The same reference characters indicate the same parts in all the views.

Let A designate a suitable base which is preferably composed of insulating material as wood. Upon this base are mounted two separated contacts A' and A² which are held in place by binding posts A³ and A⁴ to which lead circuit wires A⁵ and A⁶ from other binding posts A⁷ and A⁸. To these binding posts

2
A⁷ and A⁸ lead the main circuit wires A⁹ and A¹⁰. The binding posts A⁷ and A⁸ are normally separated except when the contacts A' and A² are connected by the circuit closing 5 part A¹¹ mounted on the arm A¹² and connected with the latter by an insulating piece A¹³. A movable arm A¹⁴, however, is employed and adapted to engage two contacts A¹⁵ and A¹⁶ connected with the respective 10 binding posts A⁷ and A⁸. In this case the arm A¹⁴ is connected with a rotary part A¹⁷ and when thrown to the dotted line position in Fig. 1 closes the circuit independently of the contacts A' and A². This arm A¹⁴ being 15 an ordinary feature or circuit-closing device, nothing is claimed thereon in this application.

The circuit closing arm A¹² (see Figs. 3, 4 and 7) is made fast to an arbor B journaled in the clock casing and actuated by a spring O which operates the alarm mechanism of a 20 clock such as we have chosen to use to illustrate our invention. The recoil of this spring rotates the arbor B and this movement actuates the gear 8 which meshes with a pinion 9 fast on an arbor B' carrying a gear 10 the latter meshing with a gear O' fast on an arbor O². This arbor O² is also provided with an escapement wheel 12 engaged by an escapement 13 fast on a vibrating spindle 1 25 journalized in the clock casing.

In the ordinary performance of the alarm function, the rotation of the arbor B acts through the train of gears above described to rotate the escapement wheel 12 whereby the 30 vibrating spindle 1 is actuated through the instrumentality of the escapement 13. This spindle 1 carries an arm 7 which vibrating with the spindle 1, acts on a gong to sound the alarm. In my improvement the gong is 35 dispensed with and this vibrating hammer arm 7 is engaged by an auxiliary arm A¹⁸ connected with the arm A¹², when the latter has reached the limit of its circuit breaking movement. By reason of this expedient, the 40 operating mechanism is locked against movement after the circuit-breaking function has been performed.

Referring now more especially to Figs. 3 and 7 let C designate the arbor upon which 45 the hour hand is mounted. A gear C' is fast on the arbor C and meshes with a pinion C² on the arbor C and meshes with a pinion C² suitably journaled in the clock casing. This pinion C² meshes with a gear 4 carrying a hub 5 having an offset C³ formed in its upper face. 50 This wheel 4 is loose on an arbor C⁴ upon which is mounted a small hub C⁵ provided with a pin 6 adapted to enter the offset C³ of the hub C⁵, when the wheel 4 has moved sufficiently to bring the offset into line with the 55 pin. The wall of this offset is vertical on one side and inclined on the other, and the central portion of the hub is hollow to receive the small hub C⁵ when the pin 6 registers with the 60 offset. When the arbor C⁴ is turned to bring

the projection 6 out of the offset C³, the pin 6 engaging the inclined side of the offset forces the wheel 4 and the hub 5 downwardly on the arbor C⁴ and against a spring 3 whose tendency is to raise the wheel 4 and its hub as soon as the pin or projection 6 is brought into 70 line with the offset. The turning of the arbor, however, to bring the pin or projection 6 out of the offset forces the wheel and spring 3 downwardly whereby a projection C⁶ of the spring engages an arm 2 rigidly connected 75 with the vibrating spindle 1, whereby the latter is locked against vibration. In this way the entire train of gears adapted to be actuated by the spring O, is locked against 80 movement.

To the lower extremity of the arbor C⁴ a hub C⁷ is attached (see Fig. 2), whereby access is given to the operator to adjust the arbor, to bring the pin or projection 6 to any desired position with reference to the offset 85 C³. The extremity of the arbor C⁴ remote from the hub C⁷, is provided with a hand or pointer C⁸ (see Fig. 1) which is adapted to move around a dial C⁹ upon which are marked numerals from 1 to 12. 90

In the operation of the device, if it is desired that the circuit shall be broken at ten o'clock, the arbor C⁴ is manipulated to cause the hand C⁸ to point to the numeral 10 on the dial C⁹. The wheel C⁴ together with its hub 95 5, is continually in motion through the instrumentality of the ordinary clock mechanism, and makes a complete revolution every twelve hours. Now by the time ten o'clock has arrived, the pin 6 of the hub C⁵ will be in 100 position to register with the offset C³ whereby the wheel 4 and the hub 5 are raised by the recoil of the spring 3, whereby the said spring is moved sufficiently to disengage it from the arm 2 of the vibrating spindle 1, thus releasing 105 the spindle, and allowing the escapement wheel to rotate through the instrumentality of the spring-actuated arbor B and the interposed train of gears heretofore described. Assuming that the circuit breaking arm A¹² 110 has been moved to the position shown in Fig. 1, thus closing the circuit through the instrumentality of the part A¹¹, the movement of the arbor B will throw the circuit breaking arm A¹² to the dotted line position in Fig. 1, thus breaking the circuit. When this circuit 115 breaking arm has reached the dotted line position in Fig. 1, its arm A¹⁸ will engage the arm A⁷ connected with the escapement 13, and lock the escapement together with the escapement wheel and the train of gears from further movement. When it is again desired to close the circuit, the arm A¹² is again moved to the full line position shown 120 in Fig. 1, and the hand C⁸ set for any desired hour as heretofore described. When this hour has been reached, the arbor B will again begin to move and the operation heretofore

125

described will be repeated. From this explanation it will be readily understood that the circuit may be automatically broken at any desired time.

5 Having thus described our invention, what we claim is:

The combination with clock mechanism provided with alarm actuating devices, of a circuit breaker connected with the said devices and arranged to be actuated thereby, the circuit breaker having a part arranged to engage a part of the alarm mechanism and

lock the latter against movement when the circuit breaker has reached its limit of movement after breaking the circuit.

15

In testimony whereof we affix our signature in presence of two witnesses.
